UNITED STATES PATENT OFFICE.

BENJAMIN F. OTTO, OF HARMONY, PENNSYLVANIA.

DESIGN FOR A BUTTER MOLD OR PRINT.

SPECIFICATION forming part of Design No. 31,821, dated November 14, 1899.

Application filed October 14, 1899. Serial No. 733,677. Term of patent 7 years.

To all whom it may concern:

Be it known that I, BENJAMIN F. OTTO, a citizen of the United States of America, residing at Harmony P. O., in the county of Butler and State of Pennsylvania, have invented a certain new and useful Design for a Butter Mold or Print; and I do hereby declare the following to be a full, clear, and exact description thereof, reference being had to the accompanying drawing, which forms a part of this specification.

In the drawing I have shown a perspective view of my design for a butter-mold, this view being all that is deemed necessary to fully illustrate my design.

The leading feature of my design consists in the diagonally-corrugated bottom and the inwardly-tapering sides and ends of the butter-receptacle.

In the drawing, A represents the ends and B the sides of a box-shaped receptacle which tapers slightly inward at the bottom and hav-

ing its upper edges rounded or chamfered, as at G, said chamfer commencing at the inner edges and sloping outward.

C is a diagonally-corrugated bottom arranged horizontally within the box and supported upon cross-pieces D, extending from one side of the box to the other.

E indicates shallow recesses formed in each end of the box and located near the bottom edges thereof.

F represents the circular heads of pins flush with the side walls of the box.

What I claim is—

The design for a butter mold or print, substantially as herein shown and described.

In testimony whereof I have hereunto affixed my signature in the presence of two subscribing witnesses.

BENJAMIN F. OTTO.
